19 Claims.

(Cl. 84—236)

This invention relates to musical instruments, and more particularly to those of the type wherein tuned vibrators are selectively subjected to impulse excitation by mechanical means. The invention contemplates especially, though not in all aspects limitatively, instruments of the piano type, wherein tuned strings or other vibrators are percussively excited by hammers under the control of a keyboard. The description will accordingly be presented largely with relation to a piano.

The apparatus for effecting the excitation of the vibrators or strings of the piano or similar instruments is commonly termed the "action." This, as currently known, is a mechanical system of relatively great complexity. This complexity has seemed both utterly necessary and quite warrantable in view of the ultimate functions which, to be satisfactory, the action must jointly perform. According to Dr. William Braid White, in his book "Modern Piano Tuning and Allied Arts" (1929; page 159): "The functions of the piano action may be described as follows: (1) to convey to the hammer a motion which shall carry it toward the string for the purpose of inflicting a blow thereon, (2) to trip the hammer immediately before its actual contact with the string, so that it shall instantly rebound without blocking the vibration (3) to permit the repetition of the hammer blow without complete release of the key . . . ."

Over two hundred years ago there was introduced, to insure the performance of the second of these functions, a construction which has ever since been considered indispensably necessary for a satisfactory action. This comprises an escapement mechanism—typically a jack which is displaced from operative position under the hammer just before hammer contact with the string—which permits the hammer to rebound to a much greater distance from the string than that to which it had been positively propelled before contact. Concomitantly introduced with the escapement mechanism was a checking mechanism—typically the so-called "back-check"—made necessary by the escapement mechanism to provide some limitation of the distance of the otherwise unlimited rebound, and later found effective in conjunction with apparatus specially introduced for the performance of the third of the abovementioned functions.

The later-introduced constructions to perform the third function have been arrangements to delay the fall of the hammer from its checked to its dormant position, so that the jack of the escape- 55

ment mechanism could restore itself to operative position under the hammer before complete key release. Typically they have comprised a so-called "repetition lever" incorporated, in the actions for grand (horizontal-string) pianos, in a complicated assembly involving adjustable tensioning and movement-limiting devices; or, somewhat less satisfactorily in the action for upright (vertical-string) pianos, a particular arrangement and balancing of parts to suppress tendencies of the hammer to return to dormant position, together with special adjustably arranged means such as the so-called "bridle-tape" to enforce that return in the last portion of key release.

15 All these arrangements reached essentially their present stage of development approximately a hundred years ago; and ever since then the piano action has resisted all attempts at obtaining a proper performance of its functions with any appreciable simplification of its construction. Unable to reduce a complexity which is actually almost appalling, the industry has simply become inured to it, and has contented itself with the mere improvement of the components of the action, methods for its manufacture, and the like.

I have observed that the complexity of the action is actually attributable almost entirely to the escapement mechanism. It is quite true that this mechanism itself constitutes only a minor part 30 of the complexity. But its presence is the immediate occasion of the need for the back-check, and for the entire construction resorted to for performing the third function abovementioned—for that function would be inherently performed, 35 and would completely disappear as one requiring special constructions, if there were no escapement.

I have further discovered that it is possible to entirely satisfactorily perform the second function abovementioned without an escapement mechanism. Prior attempts to do this have failed because of the extreme nature of the requirements. It must be recalled that the hammer must not be tripped (which term I construe and use in its broad sense, as meaning simply released or freed 40 from the propelling force of the key) until very close to the string, for otherwise the use of a relatively slow key depression—necessary for a full range of touch control—will not serve to cause the striking of the string. On the other hand unless, upon tripping, the propelling means is gotten out of the way of the hammer, the rebound of the hammer from the string to that now-very-nearby propelling means has occasioned an unwanted bounce of the hammer back to the string, or series of such bounces, in either event

ruining the tone. To alleviate the deleterious effects of this bouncing by increasing the distance of hammer from string at the time of tripping, so that the later bouncing of the hammer will not extend to reach the string, has proven almost impossible in itself, beside completely destroying the requisite ability to employ a slow key motion. It is for these and allied reasons that the indispensability of the escapement mechanism has seemed established.

I have still further discovered that, in an action from which the escapement mechanism is eliminated in a manner not compromising the features of performance above noted as requires the certainty and speed with which repetition of a note may be indulged in is not only unimpaired, but is actually enhanced over that available with conventional actions—in spite of the complete omission of the complicated mechanism specially included in the latter for the express purpose of facilitating repetition, that is, for the third function abovementioned.

Accordingly it is a general object of my invention to simplify the conventional action. And it is an object to effect this simplification without impairing the assurance of vibrator excitation with relatively slow key velocities, or the assurance of absence of bouncing of the hammer back to the vibrator after its initial rebound therefrom, or the perfection of the available repetition.

It is another object to improve the certainty and speed with which the repetition of a note may be indulged in. And it is an object to do this while greatly simplifying the action.

It is another object to provide a satisfactory action without an escapement mechanism. And it is an object to provide such an action which jointly assures vibrator excitation with relatively slow key velocities, assures absence of undesired plural contactings of vibrator by hammer, and renders available excellent repetition.

It is another object to provide such improved actions especially adapted for the excitation of relatively small and light vibrators, such as are advantageously employed with mechano-electro-acoustic translation of their vibrations into sound. And it is an object to provide such improved actions especially adapted for the excitation of relatively light strings held under relatively low longitudinal tension.

It is an object to provide a generally simplified and improved piano action.

It is an object to provide an improved and simplified construction for a piano, and in particular for an electronic piano.

Other and allied objects will more fully appear from the following description and the appended claims.

In the description reference is had to the accompanying drawings, of which:

Figure 1 is a cross-sectional view taken in a vertical front-and-back extending plane through the forward portion of a horizontal-string piano in which my invention has been incorporated in one form;

Figure 2 is a similar view taken through the rear portion of the same instrument, this figure also including a schematic illustration of the mechano-electro-acoustic translating system which may be employed in this instrument;

Figure 2a is an enlarged elevational view of the tie-member 14 appearing in Figure 2;

Figure 3 is a vertical cross-sectional view taken substantially along the line 3—3 of Figure 1;

Figure 4 is an enlargement of a small portion of Figure 1;

Figure 5 is a view generally similar to Figure 4 but illustrating the embodiment of my invention in a modified form;

Figure 6 is a view generally similar to Figure 4 but illustrating the embodiment of my invention in another modified form;

Figure 6a is a view generally similar to Figure 10 4 but illustrating the embodiment of my invention in still another modified form;

Figure 7 is a cross-sectional view taken in a vertical front-and-back extending plane through the principal portion of a vertical-string piano in which my invention has been incorporated in still another form;

Figure 8 is an enlargement of a small portion of Figure 7; and

Figure 9 is a view generally similar to Figure 4 but illustrating the embodiment of my invention in a further modified form.

A typical embodiment of my invention in an electronic piano has been illustrated in Figures 1 through 4, and the general construction incorporated in this instrument may first be briefly described. A plate or frame is provided of suitable steel beams welded together. This frame comprises a transverse front beam 1 of U-shape, open toward the front; a transverse rear beam 2 also of U-shape and open toward the front; and a plurality of front-and-back extending inverted T-beams 3 terminally welded to the transverse beams. At the front (as seen in Figure 1) the vertical part of each T-beam may be butted against and welded to the rear of the beam 1, and the horizontal part of each T-beam may be extended underneath and welded to the bottom of the beam 1. At the rear (as seen in Figure 2) the vertical part of each T-beam may be butted against and welded to the upper and lower front edges of the beam 2, the horizontal part of each T-beam being extended underneath and welded to the bottom of the beam 2. The transverse beams may be suitably inclined or tapered toward each other at the righthand (treble) extremity of the instrument to provide the usual diminishing string length; this tapering is indicated in the drawings, for example by the fractional showings 1' and 2' of the upper portions of 1 and 2. The rear portion of the wrest-plank 4 is disposed and held within the front beam 1; the front portion of the wrest-plank, whose top may be at a lower level than that of the rear portion, may extend forwardly to hold tuning pins 5.

Each string 7 may pass from its respective tuning pin 5 to the rear of the front portion of the wrest-plank 4, and may there enter a respective hole 5a which extends inclinedly downwardly to a doubly countersunk hole 1a in the rear vertical portion of the beam 1; preferably there will be provided in the forward portion of each hole 5a a respective cylindrical bushing 6, of felt, rubber, or the like. Bearing on the upper edge of the hole 1a to define the forward extremity of its active portion, the string may pass therefrom horizontally rearwardly. The holes 1a are preferably positioned so that the strings will lie in the plane of the centers of gyration of the T-beams 3, so that a given size of these beams will be most effective in rendering the frame proof against the effect of the string tension.

At the rear of the frame, as seen in Figure 2, there may be provided a bridge structure. Preferably this is of the cantilever type disclosed and claimed in my co-pending application Serial No.

229,650, filed September 13, 1938 (on which Patent No. 2,225,195 has since been issued). It may comprise a plate 8 whose rear portion is clamped, through strips 9 and screws 10, to the inside bottom surface of the top part of rear beam 2, and extending therefrom to project forwardly beyond that beam. On the bottom of a forward portion of the plate 8 is secured a string bridge 12. As pointed out in the co-pending application last abovementioned, the front-and-back dimension of the clamping strips 9 may be progressively varied transversely of the instrument, to result in a progressively varying overhang of the bridge from the clamped part of plate 8, with resulting progressive variation of the compliance of the bridge support to up-and-down vibration. Secured to the bottom of plate 8 forward of the string bridge 12, and if desired integral therewith, may be a further or "pick-up" bridge 13 of less vertical dimension than the string bridge, the function of the bridge 13 being hereinafter referred to.

It may be pointed out that for the purpose of accommodation to the presence of the T-beams 3, the plate 8 and the bridges 12 and 13 may be formed in sections separated from each other sufficiently to pass freely the T-beams 3. Preferably, however, these separate sections will be coupled to each other around each T-beam 3, for the transmission of vibrations transversely of the instrument (or longitudinally of the bridge) as though the elements under discussion had not been sectionalized. This may be done for example by securing, to the extremities of the sections of bridge 13 on each side of a T-beam 3, the respective extreme portions of an inverted U-shaped tie-member 14 straddling the T-beam, as best seen in the enlarged Figure 2a.

Each string 7 may pass across and bear up against the bottom surface of the string bridge 12, being held thereto by engagement with two pins 11. From the rear pins 11 rearwardly, and from the front pins 11 forwardly, the bridge surface may be bevelled, so that the terminal string contacts are right at the pins. Each front pin 11 of course defines the rear end of the active portion of its respective string. From its rear pin rearwardly each string may pass, inclinedly upwardly at an angle suitable for the appropriate bearing on the bridge 12, to a doubly countersunk hole 2a in the vertical rear portion of beam 2, and after passing therethrough may have its extremity anchored to a pin 15 therebelow.

The particular instrument chosen for illustrative purposes and shown in Figures 1 through 4 is intended to produce its tones through the medium of mechanico-electro-acoustic translation of the vibrations of its strings, the attendant non-necessity for a soundboard permitting the employment of the simplified cantilever vibratile bridge support already described. Typical means for translating electric oscillations from the strings may include a set of pick-up electrodes 16, preferably in the form of inverted screws adjustably threaded through the pick-up bridge 13 and plate 8 (which preferably are formed of insulating material such as "Bakelite"). The heads of the electrode screws 16 may be in spaced relation to the respective strings 7, while their upper extremities may be slotted for easy screwdriver adjustment of the spaced relation. In the interest of simplicity Figures 1 and 2 have illustrated only one string 7 and its pick-up electrode 16; but it will be understood that at least

one of each per note will be employed, as indicated for example in Figure 2a. Further as indicated in Figure 2a, some convenient means may be employed for electrically interconnecting the several electrodes, such as the conductor or soft copper wire 17 wrapped or threaded from one to another in succession above the plate 8.

A typical completion of the translating apparatus along well-known lines has been schematically illustrated in Figure 2. Between the pick-up electrodes 16 on the one hand and the strings of the instrument on the other there may be electrically connected in series a source 20 of electrical energy and a resistance 21 (connection to the strings being conveniently through the medium of the rear beam 2). If the source 20 be operated as a high-voltage D. C. source, it serves to charge the capacity between strings 7 and the pick-up electrodes 16 and, because of resistance 21, oscillatory variations in that capacity caused by string vibration will cause a corresponding oscillatory variation in the voltage across the capacity. If the source 20 be operated as a super-audible-frequency A. C. source, it serves to send through the strings-to-electrodes capacity a current whose amplitude, again in view of resistance 21, will be modulated or oscillatorily varied at the string vibrational frequencies. In either event the oscillatory components in the voltage across the strings-to-electrodes capacity may be transferred, as through a coupling condenser 22, to the input of an amplifier 23 (which, in the case of the A. C. operation of source 20, will also be operated as a demodulator). The output of the amplifier 23, comprising amplified electric oscillations representing the vibrations of the strings 7, may be subjected to any or all forms of control known in the art, non-limitatively including control of amplitude as by potentiometer 24 operated by pedal 25, and may be further amplified and translated into sound by amplifier 26 and loud-speaker 27, respectively.

Resistance 21 and condenser 22, and the leads and terminals connected thereto, may be suitably electrostatically shielded, as schematically indicated by shielding 28 in Figure 2. Shielding of the electrodes 16, which is usually sufficiently provided inherently by the strings insofar as the under-side of the electrodes is concerned, may be carried out above the electrodes by a conductive plate or member 29 hinged to the top of beam 2 and extending to overhang the electrodes; this member has been illustrated in partially raised position in Figure 2.

The frame or plate constituted by beams 1, 2 and 3, and thus the wrest-plank, bridges, strings, pick-up electrodes, etc., is held in the case of the instrument in some known manner not necessary herein to show, though preferably according to the vibration-insulation teachings of Patent No. 1,912,293 to me. Forming a part of the case of the instrument is the key-bed 30, seen in Figure 1. When the front finishing rail 31 is removed from the key-bed, the removable part of the action may be slid from the front into its place on the key-bed. In the form of my invention illustrated in these figures, this removable action portion includes the usual framework formed by front, center and rear rails 32, 33 and 34 respectively, held in proper mutual relationship by front-and-back extending strips 35. The keys 36 are pivoted on the center rail 33 in the usual manner, and may be provided with the usual guiding arrangements at the

front, including guide pins 36a extending upwardly from front rail 32 and felt washers 36b surrounding the pins. In the illustrated form of the invention the rearward extension of the keys proper is stopped short of the rear rail 34; but to the rear bottom surfaces of the keys are secured respective bars or members 37 of rectangular cross-section, these extending rearwardly to overhang the rear rail 34 and normally to rest thereon through the felt or like strip 38. The bars 37 may for example be of metal, and may serve to properly weight the key—as well as to constitute an active rear portion at a space-savingly small elevation above the key-bed.

When in position in the instrument the rear rail 34 of the removable action portion may abut (through a very thin felt strip 39 if desired) against a transverse vertical block 60 secured to the top of the key bed 30. To the top of the block 60 is secured a forwardly overhanging transverse horizontal block 61. To the bottom of the latter block may be secured a felt strip 62 which may form an up-stop for the effective rear portion of each key (i. e., for the bar 37), the washers 36b which form the usual front down-stops for the keys being adjusted to check the key motion coincidentally with the felt strip 62. The provision of 62 as well as 36b is desirable in order that the key motion in the vicinity of the hammer shall be stopped at a discrete point, without the accuracy-impairing influence of the bowing or whipping which might otherwise take place throughout the key length, and the like.

Attention may now be directed to the mechanism interposed between each bar 37 (which has been seen to constitute the active rear portion of the key) and the respective string—this constituting a typical embodiment of the great simplification of the action according to my invention. In its most basic aspect the invention is not limited as to the form of the hammer or as to its mode of movement relative to the key. I have found, however, that a very light cylindrically shaped hammer, provided with an appropriate head and moved simply in an axial direction toward and away from the string, is admirably adapted to the excitation of the relatively light, low-tension strings which are preferably employed in an electronic piano of the disclosed construction, and such hammers have been illustrated as 46 in Figure 1 and in the enlarged fractional Figure 4.

Each hammer may comprise a cylindrical side wall 47; a button or plug 48 closing its bottom extremity; and a button or plug 49 closing its top extremity—the button 49 preferably having a top surface which is convex, and whose diameter is greater than that of the hammer side wall 47 so that a shoulder is formed therewith. These elements may be formed of any suitable though preferably light material—for example, of aluminum or aluminum-alloy, or of plastic material such as "Bakelite"—and may be cemented or otherwise firmly secured together. If desired there may be substituted, as a material for the top button 49, a material appropriate to the striking of the string, such for example as leather or hard felt, in which case the button will form the head of the hammer. I have preferred, however, and have illustrated, a covering 49a over the button 49, the button and covering then together constituting the hammer head, in which

case the special material need not be employed for 49.

The hammers may be retained for vertical axial movement in respective felt-bushed holes 42 in a rail 43 extending transversely across the instrument, the heads of the hammers normally resting on a thin felt strip 45 secured on top of the rail. The desirable normal spacing of hammer-head from string (typically of the order of $\frac{3}{8}$ "') may require that the top portion of the rail 43 be cut away to admit the lower portions of the T-beams 3 (to the bottoms of which the rail 43 may be secured). The rail may be effectively restored to normal top level on each side of the vertical part of the T-beams by small blocks 44, secured on top of the horizontal portions of those beams, as seen in Figure 3. Bushed holes falling within the width of those horizontal portions are of course extended therethrough and through the blocks 44 thereabove.

Each hammer terminates at a distance above a respective one of the key-extensions or bars 37. Each key is arranged upon depression (of its forward extremity) to impart a rising movement to the hammer, and this is simply done by providing on each bar 37 below the respective hammer a capstan or hex-headed screw 40 threaded downwardly into the bar. The vertical position of the head of screw 40 is of course adjustable by rotation of the screw. While the primary purpose of this adjustability is a function hereinafter made apparent, it may here be noted that the proportioning of the parts is such that there will normally be a slight clearance between the top of the screw 40 and the bottom of the hammer, permitting the free removal and insertion of the removable action portion.

Ordinarily the mechanism interposed between key and string comprises not only the hammer but also the escapement, checking and repetition mechanisms. For all these latter I substitute a bounce-suppressing means, which I have found it possible to construct in so effective a form that the energy of the hammer, rebounding from the string, will be attenuated to the extreme degree necessary to preclude bouncing of the hammer back to the string—even though the distance through which the rebound occurs, and through which a bounce would bring the hammer back into the repeated contact with the string, be only a tiny fraction of the total original hammer stroke. Such a result has hitherto been thought quite incapable of achievement; and so it is, if there be relied on simply the absorption of hammer energy occurring in a pad or the like against which the hammer rebounds and which is made of one of the felt, leather or like materials which in piano construction are always resorted to for the performance of shock-insulating and similar functions. (Such materials are in their general nature fibrous; their largely inter-secured fibres, following deformation of the material, tend to restore themselves to original arrangement with very little work; and their reactions to deformation are therefore essentially resilient rather than energy-absorptive.)

I have found that satisfactory bounce-suppressing means may be constructed according to either of two principles, though I prefer one in which both principles are aptly combined. One principle is that of energy opposition—by a mass moved at appropriate times into opposing impact against the mass of the hammer (or, when this mass is a part of the hammer, into opposi-

ing impact against the residual mass of the hammer). The other principle is that of energy absorption—but with a material of an entirely different order of effectiveness from those above-mentioned.

I may here note that the type of energy-absorptive material which I have found to have the entirely different order of effectiveness is one whose deformation and restoration involves much work; it may generally be described as an effectively fluid mass characterized by a high viscosity. I use the term "mass" rather than "substance" to indicate that the fluidity represents a relative movement of particles of the material, whether those particles be the molecules of a truly fluid or semi-fluid substance, or individual larger particles of a solid substance which together form an agglomerate mass. I use the term "viscosity" in its accepted sense as to fluids and semi-fluids, and in its obviously equivalent sense as to an agglomerate. By way of examples of such a mass of essentially fluid or semi-fluid substance may be mentioned masses of tar, "Viscoloid," gum (for example in such form as candy gum drops), jelly, putty, plasticized clay, oil, natural resins, synthetic resins, etc. By way of examples of such a mass of individual solid particles may be mentioned agglomerates of sugar, salt, sand, fine gravel or stone, carbon granules, lead or other metallic particles, and the like. It will of course be understood that the foregoing examples are presented simply to show typical kinds of material of the general nature to which I resort, and have not been set forth with any effort at special arrangement in respect of their relative viscosities—which may vary considerably with precise chemical compositions (as in the case of fluids or semi-fluids), with particle size (as in the case of the agglomerates), and with other factors. It will also be understood that the best choice of a preferred material depends not only on available high viscosity, but on ease of handling and embodiment in the construction otherwise contemplated, imperviousness in that construction to chemical or physical change or deterioration with time or use, and the like.

The embodiment of my invention illustrated in Figures 1 through 4 utilizes jointly the two principles above-mentioned. They are made effective therein simply by the filling of the hollow hammer 46, preferably to a major fraction of its height, by one of the materials above-mentioned—preferably one of the agglomerates, such as fine gravel. The special and salutary effects for which this simple structure is responsible will become apparent from a consideration of the operation of the action.

As key depression is begun the screw 40 will almost at once be brought up into contact with the bottom of the hammer 46. As key depression is continued the hammer, its bottom now driven by screw 40, will be propelled toward the string. Very slightly before the hammer head 48 reaches the string the key motion will be stopped by impingement of 37 on 62. The momentum of the moving hammer, however, causes it to continue its movement; and since it is now free of connection with the key, it may in a broad sense be said to have been tripped. Travelling the slight distance from tripping point to string, the hammer strikes the string and rebounds downwardly therefrom. The element which drove the hammer upwardly—the screw 40—has not been displaced laterally from its driving path by any

escapement mechanism, nor has it been retracted downwardly (unless in the exceptional case of extreme staccato key manipulation). It therefore occupies the position it had when the hammer was tripped; and accordingly the distance of free rebound of the hammer is only equal to the small distance of its original movement after tripping.

In the absence of the special features of my invention, the hammer, striking the screw 40 at the conclusion of its very short rebound, would bounce upwardly again through the same small distance to strike the string a second time. Indeed, if the original key velocity had been at all great, the hammer might repeat the rebound-bounce cycle, or string-to-screw oscillation, several times, and thus cause a third or even further strikings of the string. But there are two effects of the effectively fluid mass 50 which severally and jointly act to suppress this bouncing.

During the upward movement of the hammer this mass, already urged by gravity to occupy the lowest possible position within the hammer, undergoes little movement within itself or relative to the hammer. But when the hammer movement is stopped and reversed by its striking of and rebounding from the string, the momentum of the mass 50 causes it to continue upwardly into impact against the bottom (interior) surface of the hammer head 48. In view of the effectively fluid nature of the mass 50, this impact will not be entirely discrete, but will be effectively distributed over a minute time interval. By proper choice of the extent to which the filling of the hammer is carried, this impact or at least the principal portion thereof is readily caused to occur during the rebound of the hammer—i. e., after it has begun its rebound from the string but before it has come back into impingement against the screw 40. This impact of the upwardly moving mass 50 against the downwardly moving mass of the hammer offers an abrupt opposition to the kinetic energy of the latter, a large percentage of which is thereby dissipated in the form of heat attendant on the impact. The hammer thus reaches the screw 40 with much of its kinetic energy already dissipated by the described impact.

The first effect does not stop here, however. By the end of the hammer rebound the mass 50 has come to occupy essentially the highest possible position within the hammer, and is moving downwardly with the hammer. When the downward hammer rebound is stopped by the screw 40, the momentum of the mass 50 causes it to continue downwardly into impact against the top (interior) surface of the hammer bottom 48. This impact or at least the principal portion thereof will occur well before there has been completed any string-ward bounce of the hammer which tends to result from such kinetic energy as the hammer may still have after the earlier (above described) impact-dissipation. This second impact of the mass 50, now moving downwardly and directed against the hammer now tending to move upwardly, offers an abrupt opposition to the residual kinetic energy of the hammer—which is thereby so much further attenuated that the hammer cannot reach the string for the unwanted second striking, if not entirely overpowered or reversed in sign.

The second effect acting to suppress the bouncing is the large absorption of the energy of the hammer after string striking by the movement

of effectively fluid mass 50—which is extremely effective by reason of its appropriately high viscosity. Because of the viscosity of the mass 50 (or its resistance to internal movement or deformation and so to any movement within the hammer), a large portion of dissipated kinetic energy is effectively added to the kinetic energy of the hammer proper in the striking of the string; thus, in a broad sense the mass 50 forms a part of the hammer.

When the hammer has struck the string the ensuing above-described movement of the mass 50 involves much work, and in this work a large part of the total kinetic energy is dissipated. Again, when the rebounding hammer has struck the screw 40 the ensuing above-described further movement of the mass 50 involves much further work, and in this work a large part of the residual total kinetic energy is dissipated.

These viscous dissipations are essentially independent of, but additive to, the impact-produced dissipations above described. The total effect of all is such an extreme degree of energy attenuation that the tendencies of the hammer to bounce upwardly from the screw 40 are only of the feeblest nature. This is true for the strongest key blows, or highest key-depression velocities—for, while these impart to the hammer the greatest amplitudes of kinetic energy, there is a corresponding increase in the violence of the opposing impacts and in the degree of the internal movement of the mass 50, with corresponding increase in effectiveness of both types of energy dissipation.

Accordingly the distance of the hammer head from string at the time of tripping may be made very small (as of course is desirable for certainty of string excitation at low key velocities) without danger of unwanted bounce-produced second striking; typically it may be brought down to the order of $\frac{1}{10}$ th or $\frac{1}{12}$ th of the total hammer stroke. Preferably in practice it will be made just as small as consistent with dependable elimination of the second strikings under any conditions—this being the primary function of the adjustability of the devices 40, which will be seen directly to influence this distance. When this is done the availability of dependable excitation with low key velocities has been found very satisfactory and quite comparable with that obtainable in conventional pianos.

In Figure 4 there has been shown, secured to and forming the external surface of the hammer bottom 48, a very thin leather or hard felt disc 48a. The use of this is frequently desirable to eliminate "clicks" or noise in the operation of the action. It will be understood, however, that it is neither necessary nor significantly effective in the suppression of bouncing—the structure for which function has already been detailedly described.

Infinite perfection in the characteristic of dependable slow-velocity excitation is of course not available even in conventional pianos—and this in spite of the fact that they inherently incorporate arrangements which favor this characteristic. Such arrangements, which are inherently comprised in their very complicated actions, cause the gradual building up and sudden release of a certain additional impedance to key depression at a late point in that depression, as is very familiar to all piano players. This sudden release causes a given depressing force exerted on the key to automatically increase the terminal key velocity relative to that which it will be versus out to adequately equal out at the instant of release. This results in a

would otherwise be, increasing the certainty of sufficient hammer velocity to insure string striking in spite of weak key-depressing force. Although highly satisfactory actions according to my invention may be constructed in spite of the lack of any effect such as this, they may be rendered still more perfect that conventional ones by the inclusion of an extremely simple means for gradually building up and suddenly releasing some additional impedance to key depression. Although ordinarily not necessary, a still greater simulation of conventional actions in respect of "feel" to the player is also provided by the inclusion of this means.

This means may conveniently be a collapsible spring means, and a simple embodiment of it has been illustrated in Figure 1. Held above the rear portions of the keys proper, as by suitable posts 65 extending downwardly into the front-and-back action strips 35 abovementioned, is a horizontal plate 66 having front and back down-hanging flanges 67 and 68, respectively. Horizontal slots 67a and 68a may be made in the inner vertical faces of these respective flanges, and in these slots may be disposed the respective extremities of light leaf springs 69, one above each key. These springs may be a trifle longer than could be accommodated in perfectly flat elevational configuration between the bases of the two slots, so that they are necessarily somewhat bowed; and they are formed or tensioned so that they will normally bow downwardly. Furthermore they are so arranged that even though a force be applied tending to reverse the bowing to an upward one, this force can be effective for only part of the spring, so that the normal tendency to resist a double bowing (i.e., reversed between parts of the spring) will be sufficient (preferably just dependably sufficient) to cause the downward bowing to be immediately restored on removal of the force. Such an arrangement may be carried out, for example, by arranging one of the slots (e.g. forward slot 67a) so close to the bottom of the plate 66 that the forward portion of the spring is prevented from assuming the configuration appropriate to simple upward bowing of the whole spring. Figure 1 illustrates in dotted lines the approximate configuration which one of the springs 69 will temporarily assume so long as an upward force is applied to it in its rear portion.

Carried by the key underneath the rear portion of the spring 69 is an upward projection 70, which may for example be the rounded or oval head of a screw 70a which serves to hold the bar 31 to the bottom of the key. The projection 70 is of an appropriate height to impinge against the bottom of the spring 69 in the later part of key depression. Following this impingement the continued key depression progressively deforms the spring 69 and builds up therein an increasing impedance to the key depression; but shortly the spring has been sufficiently deformed so that it finds it easiest to and does snap through to the dotted illustrated, reversely curved configuration. This snapping through suddenly releases the impedance progressively added by the spring, occurring at a late point in key depression, it has the above described effect of automatically increasing the terminal key velocity. After the snapping through, the very small residual tendency to restore to downwardly bowed configuration is of negligible noticeability so long as the key is held depressed, but is sufficient to restore the downward bowing

upon key release. It will of course be understood that the impedance which it is desirable to add by an arrangement of this character is at maximum of a relatively small magnitude, and that the constants of the springs 58 will be chosen appropriately to this fact.

In connection with the screw 70a, there may be noted an advantage of employing this as a sole means for retaining the bar 37 against the bottom of the key proper. This advantage is that the bar may then be subjected to any slight lateral adjustment (about the screw as a pivot) which may be necessary to accurately align the energy-absorbing device 58 with the bottom of its respective hammer. The screw 70a may for example be threaded through the bar 37, and after tightening the bar in any desired adjustment may be locked by tightening a lock nut 70b against the bottom of the bar.

In the description of operation incorporated above there has been no special mention of the operation as to repetition, or upon the re-depression of the key after an incomplete release thereof. But since the hammer bottom comes essentially instantly, after string striking, into a renewed continuous contact with the screw 40 (that is, continuous subject only to the inconsequential exception of the very slight spacing when the key is fully released), it will be apparent that the action is inherently adapted to perfect repetition with just as minute a degree of key release as will provide any opportunity at all for significant re-depression. Simply stated, the otherwise always present problem of providing for satisfactory repetition has been not merely solved, but altogether eliminated as a problem, in connection with the elimination of the escapement.

The instrument of Figures 1 through 4 has so far been described without reference to the usual string dampers, or vibration-terminators. These may of course be provided, fundamentally in the customary arrangement of normally resting on the respective strings, being respectively raised therefrom by depression of the respective keys, and being all raised as a unit by depression of an appropriate pedal. I have, however, incorporated the dampers in this instrument in a particularly simple manner, which may now be described.

The dampers may comprise suitable felt pads 71, respectively secured to the bottoms of blocks 72. In the side of each block may be secured the upper extremity of a respective damper rod 73. At some distance below the bottom of its damper pad 71 each rod 73 may be provided with an offset 73a, to substantially align below the respective string the portion of the rod which lies below the offset. This lower portion of each rod may pass through a respective felt-bushed hole 74 in a transverse damper rail 75, which may for example be conveniently formed as a rearward extension of the lower and middle portions of hammer rail 43; when the damper rests on the string the respective rod offset 73a may be slightly above the top of the rail 75. From the rail 75 the rods 73 may extend downwardly to terminate slightly spaced above respective hard felt or other durable pads 76, which are respectively secured on top of the several bars 37 behind the devices 40. It will be understood that the very first part of key depression will bring the respective felt pad 76 into impingement against the bottom of the respective damper rod, and

5 that the continued key depression will raise the respective damper from the string.

To retain the dampers against rotation about their rods 73 I employ a simple arrangement which may comprise a respective pin 77 extending forwardly from each damper block 72 into a respective vertical slot 78 cut in a transverse vertical plate 79, which by reason of the several slots 78 therein may be likened to a comb with upwardly directed teeth. The top of the plate or comb-member 79 may be clamped between the front and back portions of a rail 80, disposed diagonally forwardly of and above the dampers. By this simple arrangement the dampers are retained against rotation without recourse to the specifically pivoted individual damper flanges and attendant parts customarily employed.

10 A limit for the upward movements of the dampers, so that they will not appreciably overshoot their intended rise by reason of momentum developed on faster key depressions, may now be associated with the dampers themselves. This 15 may consist simply in a felt or like strip 82 secured to the bottom of a rail 81 which may be fixedly mounted at a suitable elevation above the dampers.

20 To lift all the dampers at once from the strings, a suitable pivoted pedal such as 83 acting through rod 84 may upon depression lift the rail 80 and thus the plate or comb-member 79. It is to render this plate-lifting effective on the damper pins 77 that the slots 78 are not cut through to the bottom of the plate 79, but that instead the bottom portion of the plate is made transversely continuous, with the pins 77 normally disposed slightly thereabove. To establish a proper path 25 for the limited upward movement of the rail 80 by the pedal, arms such as 85 may be secured to the rail and may extend a distance rearwardly 30 therefrom to fixed pivots such as 86.

35 It will be understood that while I have specifically mentioned one of the agglomerates as a typical material for the effectively fluid mass 58 in connection with Figures 1 through 4, there may be substituted therefor a semi-fluid or fluid—preferably the latter, since the very restricted space in which it is employed in this embodiment tends to require a reasonable fluidity so that the desired movements will actually occur. Figure 5 illustrates this modification, the mass in question appearing as 51 therein, and comprising for example an oil of quite high viscosity.

40 While I prefer to rely on the joint action of both of the effects discussed above, I may rely wholly or almost entirely on the first, or opposing-impact, one alone. In such a case, for example, the effectively fluid mass 58 may be replaced by a discrete mass. This I have illustrated in Figure 6, wherein the hammer proper may again be as in earlier figures, but wherein there is provided internally thereof a solid rod 62 of length somewhat less than the internal hammer length.

45 If desired, at the ends of this rod there may be provided deformable “bumpers” of viscous material, so that there will be an energy-absorbing action supplementing the opposing-impact action at least at and about the instants of those impacts. A bumper 53 carried by the rod 62 is shown at the top of the latter. This may 50 for example comprise a small approximately hemispherical mass 53a of viscous material, preferably one of the semi-fluids; and, to prevent any possible sticking as well as to provide a slight

but definite urge to restoration after deformation, a very thin covering 53b of rubber stretched over it and securing it to the rod. A similarly active bumper 54, this one for example loose within the hammer below the rod 52, is shown as comprising the very thin rubber sphere 54b filled with the mass 54a of viscous material.

A better supplement to the opposing-impact action of the discrete mass or rod 52 may be provided be a means offering an energy-absorbing action—preferably a viscous one—during all movements of the mass 52 relative to the hammer proper, instead of merely upon its impacts. While such a means may take a variety of forms, it is very conveniently provided by a filling of oil or the like within the hammer surrounding the rod 52. Such a filling has been illustrated as 55 in Figure 6 in addition to the bumpers 53—54, though it will be understood that ordinarily one or the other, rather than both, these expedients would be employed.

Particularly if the diameter of the mass or rod 52 be made almost as great as the internal diameter of the hammer proper, the oil filling need not be a complete one. Thus in Figure 6a I have shown the mass or rod 52' (with which no bumpers are illustrated) surrounded with only a very small quantity of oil 55'. This produces a structure which I have found especially effective.

Particularly in the constructions of these Figures 6 and 6a, it may be noted that the movement of the loosely carried mass (e. g., 52') upon hammer impacts may not always extend to produce an impact of the mass against the hammer. This, however, does not preclude an effective action; for the movement of the mass which does occur deforms or internally moves the viscous material (e. g., oil 55'), which is very effective to absorb the energy of the hammer.

In Figure 7 I have shown another embodiment of my invention, in a piano which may for example also operate electronically, but which is of upright or vertical-string arrangement. Its general construction, illustrated for simplicity in a single figure (Figure 7) without attempt to indicate tapering of the lengths of progressive strings, may first be briefly described. The plate or frame is again formed of suitable steel beams welded together, but the transverse beams have been shown by way of variation as of L-shape; these are the top beam 101 and the bottom beam 102, the vertical portion of each beam extending upwardly and the horizontal portion forwardly from the angle therebetween. T-beams 103 may extend between the beams 101 and 102, their central cross-sectional portions being forwardly directed and terminally butted against and welded to the horizontal portions of 101 and 102, and their cross portions being butted against and welded to the vertical portions of 101 and 102. The wrest-plank 104 may be disposed within the angle of beam 101, and may hold the forwardly extending tuning pins 105; from them the respective strings 107 may pass downwardly over a ledge 106a which may be formed by the forward edge of beam 101 and which defines the upper extremity of the active string length.

The string bridge 112, whose rear portion may be extended upwardly to form a "pick-up" bridge 113, may be held in front of the vertical portion of the bottom beam 102 near the top of the latter. To provide for vibratility of the bridge there may be interposed between it and the beam 102 a strip 108 of resilient material extending transversely of the instrument, the front and back

surfaces of this strip for example being cemented to bridge and beam respectively. If desired, as a means of damping the bridge vibration and hence increasing the rate of damping of the strings, the strip 108 may be split longitudinally and between its two portions there may be interposed a strip or mass 109 of one of the effectively fluid, viscous substances abovementioned (preferably one of the semi-fluid materials), the front and back surfaces of this material 109 contacting the bridge and beam respectively. The strings 107 will of course pass over the forward face of the bridge, engaging bridge pins 111, and may pass on down to terminate in respective pins 115 extending forwardly from the front edge of beam 102. The parts will of course be apportioned to provide a proper rearward bearing of the strings against the bridge, so that the strings supplement any other means employed in holding the bridge in the illustrated and described position. The bridge and associated transverse elements (e. g., 108, 109) may of course be interrupted at the beams 103; but the bridge may be unified for the whole instrument by tie-bars 114 straddling those beams (analogous to 14 of earlier figures), preferably secured to both top and bottom bridge surfaces.

The translation of string vibrations into sound may be effected by any appropriate translating apparatus; for example a system similar to that of earlier figures may be employed, and this has been schematically illustrated by the showing of the pick-up electrode 116.

The key bed 130, forming a part of the case 35 of the instrument (in which the unit formed by the elements already described is of course appropriately held), supports the removable part 30 of the action. This part may be very generally similar to that described for earlier figures, and 40 has been shown as including the center and rear rails 133 and 134 and the front-and-back extending strips 135 holding them in proper relationship; the keys 136 pivoted on 133; and the bars 137 conveniently employed as the rearmost portions of the respective keys and normally resting on rail 134 through felt or like strip 138.

With the vertical strings of this embodiment it is convenient to employ pivoted hammers. To provide a suitable pivoting support therefor, a rail 143 may be fixed slightly in front of the 50 strings and above the rear extremities of the bars 137; this rail may for example be held by the top extremities of screws or posts 142, whose bottom extremities may be secured in the key bed 138 and which may pass upwardly therefrom at suitable intervals. The forward portion of the hammer rail may conveniently be employed in forming a rear up-stop for the keys; accordingly a felt strip 162 may be secured to its bottom, to be impinged on by the rear portions of the bars 137 upon key depression.

The hammers 140 for this embodiment may be very simply formed from flat, light metal strip, bent into a closed form elevationally approximating a triangle. The rear end of the base of the triangle may form the pivoting point; and the pivoting may be carried out by a suitable cloth strip 145 folded back on itself at this point, one fold of the strip being secured to the bottom 65 of the hammer base and the other to the top surface of the hammer rail 143. Normally, since the center of gravity of the hammer lies forwardly of the pivoting point, the top fold of the strip 145 will be closed against the bottom fold, as illustrated, establishing a normal position for

the hammer. From the pivoting point the rear leg of the hammer may extend upwardly for a distance, and may then be formed to have a rearwardly directed, rounded surface or "head" 140a over which may be secured a piece 141 of leather or other suitable string-contacting material. From the rounded surface 140a the forward leg of the hammer may extend diagonally downwardly and forwardly to join the forward portion of the base of the hammer forwardly of the rail 143, completing the approximate triangle; the extremities of the forward leg and the base may be held together and bent to form a horizontal lug 140b. The top surface of the hammer rail 143 may conveniently slope downwardly to the front, so as to bring the lug 140c reasonably close to the top of the bar 137 when the hammer occupies its normal position. Downwardly through this lug 140b there may be adjustably threaded a screw 149.

I pointed out above that for bounce suppression I might rely entirely on the principle of energy absorption with the effectively fluid, viscous materials, and without the use of the opposing-impact principle which has been present in the embodiments through Figure 6. I have taken the embodiment of Figures 7-8 as a typical one in which to show this entire reliance. It will be understood, however, that there is intended no unexpressed limitation of this entire reliance to an upright-piano or pivoted-hammer embodiment, nor of the other or broader reliance to a grand-piano or axially-movable-hammer embodiment, or the like, for various features of the embodiments will obviously be interchangeable by those skilled in the art.

In broad analogy to earlier embodiments, the energy-absorptive material is again disposed to be deformed, or internally moved, by the hammer on its rebound from the string. Since the opposing-impact principle is not being relied on, however, the material is not carried by the hammer in the special manner permitting its independent movement. Indeed, it may if desired not be carried by the hammer at all, but rather by the key—and the latter disposition I have chosen for showing in Figures 7-8. Most conveniently in such a case the material will be held in some form of retaining means, which with the material itself is conveniently designated as an energy-absorbing device. It will be understood, however, that the retaining means must leave the material effectively exposed to the energy of the hammer so that it will be deformed thereby.

In Figures 7-8 I have illustrated a respective energy-absorbing device 150 carried by the key 136 (specifically by its rearwardly extending bar 137) underneath the adjustable hammer screw 149 above described. The retaining means of the device 150 may conveniently include an upright cup 152 inset into the top of the bar 137. The cup 152 is filled with a mass 151 of the material. The cup is centralized underneath the screw 149 so that the latter tends to be pushed against by the material upon key depression (i. e., rise of 137 and 150). To prevent undue penetration of the material by the screw 149, sticking of the screw in the material, and for other reasons apparent immediately below, the material 51 may in this construction be covered by a very thin membrane 153 of soft rubber, which may be considered as completing the retaining means. The membrane 153,

and thus, broadly, the retaining means, is accordingly characterized by a slight resiliency. This resiliency is sufficient to insure the repeated return of the material and device to a predetermined normal or dormant condition, but is small enough so that the predominant reaction of the device remains a viscous or resistive reaction.

While the material may be broadly any such effectively fluid, viscous material as has been typically suggested above (fluid, semi-fluid or agglomerate), I have preferred in this construction to employ a semi-fluid such as or very similar to gum in the abovementioned form. While that itself has proven quite satisfactory, it is probably somewhat less impervious to ultimate change than for example the synthetic resins—and to the latter I may point for a material which I have found especially desirable. A specific example of a synthetic resin which I have employed to great advantage is that furnished by Bakelite Corporation under the designation of "Synthetic Resin 621-193B."

This material has roughly the appearance of live rubber and, at room temperature, approximately the consistency of a candy gum drop (from which the ordinary outer surface has been removed). It is non-hygroscopic. It has elasticity, in that upon the removal of a deforming force it tends to restore to its prior configuration; but this restoration is very slow compared to that of rubber. It will extremely gradually respond to a sustained deforming force; thus to the force of gravity a solid sphere of this material will respond by flowing to a flat surface in a container in the source of about a month at room temperature. Its variation of characteristics with temperature is such that if heated to about 350 degrees F. it will flow with about the consistency of cool molasses; the normal characteristics abovementioned will be restored upon cooling back to room temperature. Heating to appreciably more than 350 degrees F., however, causes a fundamental change in the material, such that it will not thereafter recover its normal characteristics.

I may mention a method of constructing the devices 150 which I have found very convenient and satisfactory. A sufficient mass of the absorptive material, of irregular shape, has been placed in the upright cup 152, and a hot iron has been applied to soften the material so that it flows to a full level in the cup, forms a thin film on the top rim of the cup, and disposes of its excess. The cup has then been promptly inverted and pressed down against a sheet of the membrane rubber. Upon cooling the membrane rubber has been trimmed away from the periphery of the cup rim, leaving the membrane 153 secured in place by the material itself.

While I have disclosed the preferred membrane 153 as of rubber, I have pointed out that it should be very thin in order to limit the resilience which it introduces into the device. Since only limited resilience or restorative tendency is wanted, it is possible quite satisfactorily to employ other material inherently less resilient, such for example as silk or other cloth—particularly when the material 151 is itself characterized by a restorative tendency, as is the synthetic resin abovementioned.

As key depression is begun the membrane 153 of the device 150 will almost at once be brought up into contact with the bottom of the hammer screw 149. The diameter of this screw is appreciably less than the internal cup diameter, so

that there is an opportunity for the mass 151 of absorptive material to be deformed, by reduction in height immediately below the screw and increase in height therearound; at this time, however, the tendency toward this deformation is only slight, since the mass and inertia of the hammer are small. As key depression is continued the hammer, its screw 149 now driven through the device 150, will be propelled toward the string. Very slightly before the hammer head reaches contact with the string, the key movement is stopped by impingement of bar 137 on the up-stop formed by the felt strip 162; the hammer may then be said to be tripped, or freed from operative connection with the key. It will continue its movement for the short distance required for striking, and will then rebound through the same short distance, bringing the bottom of the screw 149 into impingement against the now-raised device 150. This impingement, occurring with a velocity dependent on original key velocity, will cause a corresponding degree of deformation of the material 151. The work done in this deformation absorbs a large part of the energy of the rebounding hammer; the further work done in the substantial recovery from that deformation, urged by the limited resiliencies of the material 151 and of the membrane 153, absorbs a further large part of that energy, and renders the recovery so slow as to impart only the feeblest of bouncing motion to the hammer, insufficient to carry it back to the string.

While the initial deformation of the material 151, attendant on the beginning of key depression, has been noted to be only slight, it nevertheless may be sufficient to provide a beneficial automatic effect. This deformation will comprise a slight reduction of height of the central portion of the device 150 underneath the screw 149; and this slight reduction will be the greater, the greater the key velocity. During the minute interval between hammer tripping and the completion of rebound, there will of course be essentially no restoration of this reduced height to normal. Accordingly, the greater the key velocity and thus the greater the kinetic energy of the hammer, the greater is the distance through which it rebounds from the string and thus the greater is the distance through which a bounce would have to extend in order to cause the unwanted second striking. On the other hand with low key velocities, when the minimum tripping (and rebound) distance is desirable, substantially no reduction of height or increase of distance occurs.

It will of course be understood that with this embodiment repetition is just as perfectly available as in the earlier embodiment. And, though not necessary, there may if desired be employed as an additional refinement the collapsible-spring system 65-70 illustrated and described in connection with the earlier embodiment.

Suitable string dampers, or vibration-terminators, may readily be provided in the embodiment of Figure 5. The damper for each string may be a respective felt pad 171, held at the top of a respective substantially vertical arm 172 disposed in a transverse plane behind the strings. The arm 172 may be formed of flat, light metal strip; and it will preferably be provided with flanges 172a folded forwardly from the side edges of its top portion, to embrace the rear portions of the sides of the pad 171. The bottom of the arm 172 may be a point of pivoting for the arm, 75

a suitable pivoting arrangement being described below; and at this point the material of the arm may be bent to extend forwardly, passing closely alongside the respective string through the plane of the strings, in the form of an arm 173. The arm 173 may extend to have its forward extremity normally slightly spaced above a rearward lug or projections 137a formed from the lower rear portion of the respective bar 137; and the forward portion of the arm 173 may be sufficiently weighted, as by weight 173a, to impart to the arms 173 and 172 a bias (clockwise as illustrated) urging the damping pad 171 against the respective string. Upon key depression, however, the lug 137a will be brought upwardly into impingement against the bottom of arm 173, and will rock arms 173 and 172 (counterclockwise as illustrated) to carry the damping pad 171 rearwardly out of contact with the string.

20 For supporting the dampers a transverse damper rail may be provided in the form of wooden or other members 175 secured transversely of the instrument between the successive T-beams 103; the front surface of the rail may be advantageously inclined upwardly and rearwardly. The pivoting of each damper arm system 172-173 to the rail may be carried out by a respective suitable cloth strip 174 folded back on itself at the point of juncture of the two arms, one fold of the strip extending upwardly along and being secured to the back of arm 172, and the other fold of the strip extending upwardly along and being secured to the inclined front surface of the rail 175. A stop for possible overshooting movements of the dampers may be provided in the form of felt or like strip 176 secured along the top portion of the front surface of the rail.

30 To remove all the dampers at once from contact with the respective strings, there may be provided underneath the forward extremities of arms 172 a transverse rail 180; this may for example be held at the forward extremities of suitable arms 185, whose rear extremities are pivoted to pivots such as 186 to establish a generally vertical, short arcuate path of movement for the rail 180. A pedal such as 183, acting through rod 184, may upon depression lift the rail 180 and so move all the dampers rearwardly.

40 It is to be understood that while in Figures 7-8 I have shown an energy absorbing device of one particular construction, a great number of alternative constructions are available. Two such constructions have been illustrated by the respective bumpers 53 and 54 in Figure 6. These are of course not limited, in their utility with a hammer, to association with the auxiliary or secondary mass (rod) 52—there being obvious their equivalence in operation to the devices 150, as well as the availability for them of materials similar to the mass 151 and membrane 153 of the latter devices.

50 Another typical construction I have illustrated in Figure 9—by way of example, in connection with a cylindrical, axially moved hammer such as 46. In this construction there is secured in the open bottom of the hammer 46 (for example, below a transverse disc 58 secured within the hammer a little way from the bottom) a light coil spring 57, which extends for a distance downwardly from the hammer proper. Within and around this spring is a generally cylindrical mass 59 of semi-fluid absorptive material, such as the synthetic resin abovementioned—in other words, the spring 57 is imbedded in the mass 59. The

spring accordingly functions as a resilient retaining means for precluding permanent deformation of the material 58, but is of course weak enough so that the reaction of the device as a whole is predominately a viscous one. The device may be completed by a very thin disc 59 of rubber, silk or the like adhering to the bottom of the material and precluding any sticking to the capstan or screw 40.

While not in its broader aspects limited thereto, it will be understood that the actions constructed according to my invention are particularly advantageous when, as illustrated, the mass of the hammer is a small part of the total mass moved by the key. Then there is automatically insured the absence of any feeling by the player's fingers of the rebound of the hammer. The small-mass hammer is otherwise desirable when the vibrators to be excited are relatively small and light; such vibrators are the preferred ones in instruments operating by mechano-electro-acoustic translation (such as the illustrated electronic pianos), and for these instruments my invention thus has an especial utility.

While I have shown and described my invention in terms of particular embodiments thereof, it will be understood that the details of these embodiments may be varied within wide limits without departure from the true spirit or proper scope of the invention. That scope I undertake to express in the appended claims.

I claim:

1. In a musical instrument, an exciting action for a vibrator comprising, in combination, a hammer movable to strike the vibrator; stop means against which the hammer rebounds after striking the vibrator; and means, carried by and movable relatively to the hammer, for suppressing bouncing of the hammer from said stop means back to the vibrator.

2. In a musical instrument, an exciting action for a vibrator comprising, in combination, a hammer movable to strike the vibrator; stop means against which the hammer rebounds after striking the vibrator; and means, comprising a mass moved by and relatively to the hammer, for suppressing bouncing of the hammer from said stop means back to the vibrator.

3. The combination according to claim 2, wherein there is comprised means for causing a viscous resistance to the movement of said mass relative to the hammer.

4. In a musical instrument, an exciting action for a vibrator comprising, in combination, a hammer movable to strike the vibrator; stop means against which the hammer rebounds after striking the vibrator; and means, comprising an effectively fluid mass characterized by a high effective viscosity and subjected to internal movement by the hammer, for suppressing bouncing of the hammer from said stop means back to the vibrator.

5. In a musical instruments, an exciting action for a vibrator comprising, in combination, a hammer movable to strike the vibrator; stop means against which the hammer rebounds after striking the vibrator; and visco-elastic means characterized by a predominately viscous reaction for suppressing bouncing of the hammer from said stop means back to the vibrator.

6. In a musical instrument, a key-operated exciting action for a vibrator comprising, in combination, a hammer movable to strike the vibrator; key-moved means for impelling the hammer toward the vibrator and acting as a stop for the

rebound thereof; and means, carried by and movable relatively to the hammer, for suppressing bouncing of the hammer from said key-moved means back to the vibrator.

5 7. In a musical instrument, a key-operated exciting action for a vibrator comprising, in combination, a hammer movable to strike the vibrator; key-moved means for impelling the hammer toward the vibrator and acting as a stop for the rebound thereof; and means, comprising an effectively fluid mass characterized by a high effective viscosity and subjected to internal movement by the hammer, for suppressing bouncing of the hammer from said key-moved means back to the vibrator.

8. In a musical instrument, an exciting action for a vibrator comprising, in combination, a hammer movable to strike the vibrator; stop means against which the hammer rebounds after striking the vibrator; and means, loosely carried by the hammer, for effecting a bounce-opposing impact on said hammer at the conclusion of hammer rebound.

9. In a musical instrument, an exciting action for a vibrator comprising, in combination, a hammer movable to strike the vibrator; stop means against which the hammer rebounds after striking the vibrator; and means, loosely carried by the hammer, for effecting a rebound-opposing impact on said hammer at the beginning of hammer rebound and a bounce-opposing impact thereon at the conclusion of said rebound.

10. In a musical instrument, a vibrator-exciting action without an escapement comprising, in combination, a hammer movable to strike the vibrator and to rebound therefrom; and means, loosely carried by the hammer, for effecting an opposing impact on the hammer upon its rebound from the vibrator.

11. In a musical instrument, a vibrator-exciting action without an escapement comprising, in combination, a hammer movable to strike the vibrator; a mass carried by the hammer and subjected to movement relative thereto when the hammer strikes the vibrator; and viscous damping means associated with said mass and effective upon said relative movement.

12. In a musical instrument, an exciting action for a vibrator comprising, in combination, a hammer movable to strike the vibrator; stop means against which the hammer rebounds after striking the vibrator; a mass carried by the hammer and subjected to movements relative thereto when the hammer strikes the vibrator and when the hammer strikes said stop means; and viscous damping means associated with said mass and effective upon said relative movements.

13. In a musical instrument, a vibrator-exciting action without an escapement comprising, in combination, a hammer movable to strike the vibrator and to rebound therefrom; means, carried by the hammer, for effecting an opposing impact on the hammer upon its rebound; and effectively viscous means subjected to deformation by the hammer upon its rebound for absorbing energy from the rebounding hammer.

14. In a musical instrument, a vibrator-exciting action without an escapement comprising, in combination, a hammer movable to strike the vibrator and to rebound therefrom; and means, comprising an effectively fluid mass characterized by a high effective viscosity and subjected to internal movement by the hammer, for absorbing energy from the rebounding hammer.

15. In a musical instrument, a vibrator-exciting

ing action without an escapement comprising, in combination, a hammer movable to strike the vibrator and to rebound therefrom; effectively viscous means subjected to deformation by the hammer for absorbing energy from the rebounding hammer; and resilient means associated with said last-mentioned means for restoring the same to a normal configuration.

16. In a musical instrument, a vibrator-exciting action without an escapement comprising, in combination, a hammer movable to strike the vibrator and to rebound therefrom; effectively viscous means subjected to deformation by the hammer for absorbing energy from the rebounding hammer; and resilient means within 10 said last-mentioned means for restoring the same to a normal configuration.

17. In a musical instrument, a key-operated exciting action for a vibrator comprising, in combination, a hammer movable to strike the vibrator; key-moved means for impelling the hammer toward the vibrator and acting as a stop for the rebound thereof; and visco-elastic means characterized by a predominately viscous reac- 15

tion interposed between said last-mentioned means and the hammer.

18. In a musical instrument, a vibrator-exciting action operated by a limitedly movable key comprising, in combination, a hammer moved by the key to a relatively small spacing from the vibrator and thereafter moved by its own momentum to strike the vibrator and to rebound therefrom through said spacing; and movement-transmitting means, interposed between the hammer and the key, yieldable in accordance with the velocity of key movement and characterized by slow recovery, whereby said spacing is caused to vary with the velocity of key movement. 15

19. In a musical instrument having a vibrator-exciting action: the combination of a depressible key included in and operating said action; and collapsible spring means rendered effective by said key in its downstroke, for first building up and then releasing an impedance to said downstroke. 20

BENJAMIN F. MIESSNER.
